FRANK P. KOBERT, OF PELHAM MANOR, NEW YORK

ELECTRIC RIVET HEATER

Application filed September 22, 1921. Serial No. 502,366.

The present invention relates to methods and means for heating metal objects, such as rivets, electrically to a forging or other desired temperature. It is an object of the present invention to devise methods and means of the character specified which will be extremely simple in operation, which will enable the heating of the desired objects, such as rivets, to take place at greater speeds and with less consumption of current and with less danger of burning or otherwise deleteriously affecting the metal objects, such as rivets, than has hitherto been possible. It is a further object of the present invention to devise apparatus for the purpose specified which will be less cumbersome and less expensive than the apparatus hitherto employed for the same purpose while at the same time having a much greater capacity and carrying out the desired heating operation more economically and efficiently.

By way of example, there is, in the accompanying drawings and specification, shown and described an illustrative embodiment of the apparatus of the invention in which an illustrative embodiment of the process of my invention may be carried out successfully. It is, however, to be clearly understood that the illustrative embodiments of the apparatus and process of my invention herein shown and described are so shown and described for purposes of illustration only.

Referring to the drawings in which the aforesaid illustrative embodiment of the apparatus of my invention is illustrated,

Figure 1 shows a side elevation;

Figure 2 shows a top elevation;

Figure 3 shows a horizontal section of the aforesaid embodiment of the apparatus of my invention taken along the line of 3-3 of Figure 1, certain parts being shown in elevation; while

Figure 4 is a detail elevational view of a portion of the machine.

Before describing in detail the aforesaid illustrative embodiments of the apparatus and process of my invention it may be desirable briefly to point out the defects of the devices hitherto used in the art for accom-

lishing the same general purpose, namely to heat metal objects, such as rivets, to a forging or other desired temperature. The rivet heaters, for example, hitherto employed, have required for the attainment of the desired degree of temperature the use of heavy transformers. Their construction furthermore has rendered their operation extremely slow, uncertain and often unsatisfactory. This is particularly so since the heating of the rivet or other metal object taking place in a single operation and without any satisfactory means, automatic or otherwise, for regulating the flow of heat current, has often resulted in burning the rivets by overheating the same.

By means of my present invention the aforesaid disadvantages of the devices hitherto employed in this art for heating rivets and the like are practically and in a highly efficient manner substantially entirely overcome, and certain advantages hereinafter more fully pointed out are attained, resulting in economy of current, and a less expensive and less cumbersome device which, within certain limits, automatically accommodates itself to varying sizes or lengths of rivets and does not burn the same, since the heating operation is conducted not in a single powerful stage but in a succession of moderate heating stages.

Referring to the drawing, there are shown at (a) rivets disposed upon a metal band or other suitable support 1. The rivets (a) are picked up, one at a time, by the person operating the machine and placed in the groove (b) in the band 1. The angle iron 2, which is a continuation of and completes the band 1, is made adjustable with respect to the stationary part of the band 1 by means of the cleats or eyelets 3, of which two are shown in Figure 2 of the drawing, and the screws 4. By adjusting the angle iron 2 by means of the slots 3' in the cleats or eyelets 3 and the screws 4, the band 1 may be adjusted to accommodate rivets of various diameters for which the machine is to be set.

While various means may be employed for intermittently advancing the rivets, I prefer

to employ the means shown comprising a sprocket chain 5 mounted on the sprockets 6 and 7. Spaced at proper intervals along the chain 5 and carried by the same are the links 8. The chain 5 is caused to move, as in the direction shown by the arrow (c), and preferably intermittently, by suitable mechanism, so that a rivet placed behind one of the links 8 in the groove (b) is advanced 10 successively into position in front of and between the pairs of upper and lower jaws or electrodes, of which any suitable number may be employed, three such pairs being shown here by way of example and being 15 respectively numbered 9 and 12, 10 and 13, and 11 and 14.

The intermittent movement of the sprocket chain 5 may be accomplished in the following manner: The sprocket wheel 7 is 20 connected to a shaft 15, which is in turn pinned or otherwise rigidly attached to a ratchet 16, as more clearly shown in Figure 1 of the drawing. Mounted on the same shaft 15 there is a cooperating ratchet 17 which has 25 teeth 17' cut in its periphery. Engaging with the teeth 17' on the ratchet 17 are the teeth 18' of a rack 18. At the lower end of the ratchet 17 there is mounted a compression spring member 19, the lower end of 30 which bears against a bracket 20. The upper end of the spring bears against the ratchet 17 and tends to push the same into engagement with the ratchet 16, as more clearly shown in Figure 1 of the drawings. The 35 two ratchets 16 and 17, together with the spring 19, are contained within a housing 21 mounted on the bracket 20, the housing 21 in turn acting as a guide for the rack 18 for which purpose the housing is provided with 40 an extension in the form of a cylindrical hollow member 21'.

The shaft carrying the rack 18 is made in two portions, 18^a and 18^b, which portions are connected by the turnbuckle 22. At the 45 outer end of the portion 18^a of the shaft carrying the rack 18 there is mounted a roller 23 mounted in the yoke 24 at the end of section 18^b and the rack shaft. The roller 23 bears against the cam 25 mounted on the 50 main cam shaft 82, as more clearly shown in Figure 3 of the drawings. A spring 26 is mounted on the rack shaft on part 18^a of the same between the housing 21 and the turnbuckle 22. The spring 26, which is a 55 compression spring, by its action against that end of the turnbuckle 22 which is adjacent part 18^a of the rack shaft, tends to push the rack towards the cam shaft in the direction indicated by the arrow (d) in Figure 60 3 of the drawing.

The cycle of operation of the parts thus far described, beginning from the cam shaft, is, therefore, as follows: The cam 25 rotates and pushes the rack periodically in a direction 65 opposite to the direction indicated by

the arrow (d) by means of the engagement of the cam 25 with the roller 23 carried at the end of part 18^b of the rack shaft. It will, of course, be apparent that the spring 26 tends at all times to keep the roller 23 70 in engagement with the cam 25. This action of the cam 25 causes the rack to rotate the ratchet 17 by reason of the toothed contact between the teeth 18' of the rack 18 and the teeth 17' of the ratchet 17. The ratchet 17 75 has teeth 17^a mounted upon its upper surface for engagement with the teeth 16^a on the lower surface of the ratchet 16, the ratchet 16 being pinned or otherwise rigidly attached to shaft 15, which is in turn rigidly pinned or otherwise attached to the sprocket wheel 7. It will therefore be seen that a complete revolution of the cam 25 causes the rack 18, by reason of its engagement with the ratchet 17, which is carried by the shaft 25 15, which also carries the sprocket wheel 7, to advance the chain member 5 one link for each revolution of the ratchets 16 and 17. By these means the rivets in front of the links are advanced one space for each revolution of the ratchets 16 and 17.

Mounted on members 26 and 27, as more clearly shown in Figure 1 of the drawing, are a plurality of transformers, here shown as three in number, and respectively identified by the reference numerals 28, 29 and 30. It will be seen that the number of transformers corresponds to the number of pairs of upper and lower jaws or electrodes 9 and 12, 10 and 13, and 11 and 14. The number of transformers that may be used may be varied within considerable limits, but for the purpose of illustration there are here shown three transformers, since this number is sufficient to exemplify the principle of the present invention. The primary terminals of the transformers are connected to the usual service line supplying alternating current, while one of the legs 31 of the secondary coil of each transformer is connected by means of a cable 34 to the respective upper jaw or electrode 9, 10 or 11. The other leg 37 of each transformer is connected by means of the cable 40 to the respective lower jaw or electrode 12, 13 or 14. Since the lower jaws or electrodes 12, 13 or 14 are preferably all constructed alike, it will be sufficient to describe the construction of a single lower jaw or electrode, such, for example, as the jaw or electrode 12. The electrode 12 is mounted on an angle casting 43, as more clearly shown in Figure 1 of the drawing. Yoked around the casting 43 is a lever 46 which is pivoted to the casting 43 by means of a pin 49. The main bearing of the lever 46 is on 100 the cylindrical rod or bearing 52, as shown in Figures 1 and 3 of the drawing.

Springs 53, 54 and 55, as more clearly shown in Figure 1 of the drawings, are provided, these springs bearing against the re- 105 110 115 120 125 130

spective washers 56, 57 and 58. These washers press against shoulders on the connecting rods 59, 60 and 61, which are in turn pivoted in the side plate 62 on the respective pins 63, 64 and 65. The side plate 62 is pivoted to the lever 46 about the pin 64. The combined compression force of the springs 53, 54 and 55 is exerted through the side plate 62 on the pivot point 64, which in turn causes the combined compression force of these springs to act upon the lever 46 about the pivot point 52. This action causes the lever 46 to tend to raise the angle iron 43 by means of the connection of the latter with the lever 46 on the pivot 49. The direction of this movement, which is upward, is indicated by the arrow (e).

The central connecting rod 60 has at the end opposite the pivot point 64 a yoke 66 connected at the pivot point 69 with a bell crank lever 72. The bell crank lever 72 is pivoted on a pivot shaft 75, as more clearly shown in Figure 3 of the drawing. The free end of the bell crank lever carries a roller 76. This roller is in contact with a cam 79 mounted on the main cam shaft 82. The pivot shaft 75 is mounted in two brackets 83 and 84, as more clearly shown in Figure 3 of the drawings.

At its upper end the angle iron casting 43 is provided with a pivot 85, about which is yoked the lever 86 pivoted about the shaft 87. By means of the levers 46 and 86 pivoted and arranged as described above, it is possible to give each of the lower jaws or electrodes 12, 13 or 14 a substantially rectilinear motion into and out of contact with the lower or unheaded ends of the rivets (a). It is, of course, to be understood that other equivalent means may be utilized for the same purpose.

The desired movement of the lower jaws or electrodes 12, 13 and 14 into and out of contact with the lower unheaded ends of the rivets (a) takes place in accordance with the following cycle of operation: The cam 79, by means of its rotation about the shaft 82 to which it is fixed, acts upon the roller 76 carried at one end of the bell crank lever 72 pivoted about shaft 75 and against the action of the springs 53, 54 and 55. The bell crank lever, through the yoke 66 pivoted at its lower end at 69, and by means of the connecting rod 60, tends to compress spring 54 and also, through the connection of the side plate 62 pivoted to lever 46 at 64, tends to compress the springs 53 and 55 which are coiled about the respective connecting rods 59 and 61.

It therefore follows that when the cam 79 is at its highest point, as shown in Figure 1 of the drawing, the springs 53, 54 and 55 will be under maximum compression and the levers 46 and 86 will be in their lowermost position, also as shown in Figure 1 of the drawing.

This position of the levers 46 and 86 corresponds to the lowermost position of the lower jaws or electrodes 12, 13 and 14. It will, of course, be understood that the object of the lever 86 is to provide proper support for the angle iron casting 43 and to cause the same to rise upward in an arc or line firmly and accurately into contact with the lower unheaded ends of the rivets (a). By means of the lever 86 I am enabled to do away with other more complicated steadyng and supporting devices for the angle iron castings 43 or their equivalents.

When the cam 79 is in its lowermost position, the bell crank lever 72 is more nearly horizontal than shown in Figure 1 of the drawing, thus causing it through its connections described above, to permit the springs 53, 54, and 55 to be free to exert their combined pressures about the pivot point 64 of the lever 46 to cause the same to be turned about its pivot 52, so that its inner end, pivoted at 49 to the angle iron casting 43, is caused to rise. This rising action of the inner end of the lever 46 causes the angle iron casting 43, steadied and supported by the lever 86, to bring the lower jaws or electrodes 12, 13, and 14, respectively, carried by the angle iron castings 43, into operative conductive relation to the lower ends of the rivets (a) and at the same time to raise the rivets so that the heads of the rivets come into operative conductive relation with the upper jaws or electrodes 9, 10, and 11, respectively.

When the lower electrodes 12, 13 and 14 have been brought into contact with the lower ends of the respective rivets (a) and have raised the rivets so that their heads are in contact with the respective upper electrodes 9, 10 and 11, the further rotation of the cam 79 merely causes the cam to swing past the roller until at a certain stage of its revolution it permits the levers 46 and 86 under the action of springs 53, 54 and 55 once more to withdraw the lower electrodes 12, 13 and 14.

Current passes through the rivet by contact of the same with the respective upper and lower electrodes, and current is permitted to pass until one stage of the heating operation, for example the preliminary or initial stage, is completed. Thereupon the lower electrode is withdrawn and the preliminarily heated rivet is passed to the second set of electrodes and the operation described above repeated and the rivet submitted to a second or intermediate heating stage. The last heating stage takes place at the last set of electrodes to which the rivet is advanced in the manner already described. After leaving the last set of electrodes the heated rivet is carried by its link 8 beyond the electrodes to where the operator may remove the same for use as desired.

It will be apparent that the circuit is closed through each rivet (a) by the rivet being raised into contact with the upper electrodes by the upward movement of the lower electrodes, thus closing the electric circuit through the secondary and causing the rivet to receive the desired flow of heating current, as well known in the art. It is to be understood that the cam 79 has such a contour that it advances the lower electrode upwardly and retains the same in raised position for a length of time which will be proportional to the heating requirements of the upper electrode. In the present embodiment shown herein for purposes of illustration, this length of time will be proportional to one dimension of the rivet, for example, proportional to its length. That is, if the rivet is longer, the circuit through it is closed sooner and the heating current accordingly maintained through the rivet a proportionately longer time. Accordingly, the device here shown and described brings about a highly effective and simple automatic adjustment of the heating current in accordance with the demands of the particular rivet held between a particular pair of electrodes at a particular time.

The cam shaft 82 is mounted in brackets 88 and 89, which brackets are fastened to the two channel iron frames 26 and 27, more clearly shown in Figure 1 of the drawings. The channel iron frames 26 and 27 are in turn connected to another channel iron frame 90 by means of the connecting rods 91. There is also provided a bracket 92 supporting an angle iron 93 suitably attached to the bracket 92 by any suitable means, on which angle iron are mounted the upper electrodes 9, 10 and 11. The shafts 52 and 87 are likewise carried by and pivoted in the bracket 92, which also carries the housing 93, in which the chain sprocket wheels 6 and 7 are mounted. Preferably, the sprocket wheel 6 is mounted on a stud 94 which is adapted to be slidably adjusted within a slot 95 to keep the chain tight. A rail 96 may be provided about the band 1 to act as a retaining wall for the rivets which are kept on the band. The machine derives its power from any suitable source not here shown by means of the tight and loose pulley 97 at the end of the cam shaft 82.

The operation of the machine will be clear from the foregoing description. By means of the embodiment of the machine I have described and the process which may be practiced by means of said embodiment of the machine, heating of the rivet takes place in successive stages by successive increments of heat serving to raise the rivet or other metal object to be heated, to the desired temperature. This is accomplished by supplying successive increments of heating current or, in other words, by passing the cur-

rent through the object to be heated in successive stages, preferably from a plurality of pairs or sets of heating electrodes. By these means a plurality of small transformers connected to respective pairs or sets of electrodes may be utilized in place of the larger and cumbersome transformers hitherto employed. The heating of the rivets or other metal objects taking place in stages, burning of the rivets or other metal objects being heated, and overheating of the same, are substantially avoided. By means of the process and apparatus described above a much quicker and more efficient heating of the rivets or other metal objects may be effected. This is particularly true if a comparatively large number of pairs or sets of electrodes is employed, in which case the heating operation may take place in more than two or three stages, as in six or eight stages or more. By increasing the number of heating stages, the number of rivets which may be heated in the machine in a unit of time is proportionately increased. It will be noted also that by means of the construction described above automatic adjustment is made for the heating demands of a particular rivet being heated by any particular set of electrodes at a particular time. Furthermore, this automatic adjustment is accomplished in a very simple and highly ingenious manner and is effective to take care of variations in the rivets that often occur in practice, or in such cases where it is desired to put through the same machine rivets of different sizes to be used for different purposes or in different parts of the same structure where the rivets are to be inserted.

It is of course to be understood that my invention is not limited to the specific embodiments thereof herein shown and described for purposes of illustration only, and that other machines may be constructed for practicing the process herein described and claimed, and that a large variety of metal objects other than rivets may be properly heated by the apparatus of the present invention, which may be modified within wide limits while still embodying the substance of the present invention.

What I claim is:

1. In an electric rivet heater, a plurality of pairs of heating electrodes, and means for bringing a rivet into operative conductive relation to successive pairs of heating electrodes to thereby heat such rivet in successive stages.
2. In an electric heater for metal objects, a plurality of sets of heating electrodes, and means for bringing each of a series of metal objects to be heated into operative conductive relation to successive sets of heating electrodes to thereby heat each of said ob-

jects in successive stages by successive applications of heating current.

3. In an electric heater for metal objects, a plurality of sets of heating electrodes, means for bringing a metal object to be heated into operative conductive relation to successive sets of heating electrodes to thereby heat said object in successive stages by successive increments of heating current, and means associated with at least one of said sets of electrodes for varying the heating current supplied at said set of electrodes in accordance with the heating current demands of the particular metal object in contact with said set of electrodes at a particular time.

4. In an electric heater for metal objects, plurality of sets of heating electrodes, means for bringing each of a series of metal objects to be heated into operative conductive relation to successive sets of heating electrodes to thereby heat each of said objects in successive stages by successive applications of heating current, and means associated with at least one of said sets of electrodes for varying the heating current supplied at said set of electrodes in accordance with the heating current demands of the particular metal object in contact with said set of electrodes at a particular time.

In testimony whereof, I have signed my name to this specification this 30th day of August, 1921.

FRANK P. KOBERT.
